UNITED STATES PATENT OFFICE.

GEORGE D. HAINES, OF PARK RIDGE, ILLINOIS, ASSIGNOR TO PORCELAIN TILE COMPANY, OF CHICAGO, ILLINOIS, A CORPORATION OF ILLINOIS.

TILED WALL OR THE LIKE.

Application filed February 23, 1928. Serial No. 256,102. **REISSUED**

This invention relates to the production of tiled surfaces of the general type disclosed in my Patent No. 1,594,614, dated August 3, 1926. The construction shown in 5 said patent comprises a foundation sheet having grooves to receive marginal flanges upon enameled sheet metal tile.

The present invention relates more particularly to the substitution, for the grooves 10 and flanges, of locating means which shall involve less expense than the grooving of the foundation sheet and which shall not weaken the foundation sheet.

This object I attain by providing on the 15 margins of the tiles tangs which are adapted to fit into rows of holes formed in the foundation sheet.

In the accompanying drawings,

Figure 1 is a fragmental view, partly in 20 section and partly in elevation, of a tiled structure embodying the features of my invention.

Fig. 2 is a perspective view of one of the 25 enameled sheet metal tiles.

While the invention is susceptible of various modifications and alternative constructions, I have shown in the drawings and will herein describe in detail the preferred embodiment, but it is to be understood 30 that I do not thereby intend to limit the invention to the specific form disclosed, but intend to cover all modifications and alternative constructions falling within the spirit and scope of the invention as expressed in 35 the appended claims.

As shown in Fig. 2, the tile consists of a metal plate 1 having marginal rearwardly extending tangs 2 which are integral with the plate 1. The outer surface of the plate 40 1 and the lugs 2 are coated with vitreous enamel, the inner side of the tile preferably also being enameled. While the tiles may be of various dimensions, they are preferably of the same width and length as standard 45 clay tile, namely, three inches wide and six inches long, the tangs 2 being approximately three-sixteenths inches long.

The wall or other surface to be tiled may 50 be of any preferred construction. Herein I have shown a framework comprising the usual vertical wooden studs 4. Upon the studs is nailed or otherwise secured a foundation sheet 5 of any suitable fibrous or mineral material. In practice, shims (not 55 shown) are inserted between the studs and

the sheet 5 wherever necessary to produce a substantially true plane surface. The sheet 5 is provided with rows of holes 6 properly spaced to receive the tangs 2, which rows of holes are arranged to present or designate 60 a symmetrical series of geometrical figures, such as the squares shown in Fig. 1. These holes may be easily formed in any suitable manner, as for example, by placing a sheet or large portion of the sheet in a machine 65 adapted to punch a large number of holes at one time. The holes preferably extend entirely through the sheet so that either side of the sheet may be utilized to receive the tile. 70

The sheet 5 having been secured in place on the studs 4, the tiles are successively coated on their backs and tangs 2 with a suitable cement and set against the sheet 5, with the tangs 2 inserted in the holes 6 75 thereby increasing the permanency of the union between the tiles and the sheet. The holes 6 also indicate the proper location of the tiles with reference to both horizontal and vertical lines, in consequence of which 80 the setting of the tiles involves no particular skill and may be rapidly effected. Because of the thinness of the layer or film of cement between the tiles, no attempt has been made to indicate said film in the drawings. 85

The vertical dimension of the sheet 5 is preferably a multiple of the width of a tile plus suitable allowance for the film of cement between adjacent tiles. The horizontal dimension of the sheet in the preferred form is a multiple of sixteen inches, the usual spacing of the studs 4. The sheet may be of any desired thickness which will afford sufficient rigidity. 95

The spacing of the rows of holes 6 will, of course, correspond to the dimensions and desired arrangement of the tiles, the width of each hole being preferably slightly greater than twice the thickness of the 100 tangs 2. As previously mentioned the surface of the sheet presents a symmetrical series of similar geometrical figures. Consequently, during the tile setting operation, the use of tiles of various lengths, which 105 are generally multiples of the dimensions of the geometrical figure designated by the holes, permits a great variety of geometrical figures or mosaics to be formed. Pleasing variations also may be obtained by 110

using tiles of various colors, or by arranging plain or colored tiles to form borders for the tiled surface. Since the positions of the tiles are determined by the rows of holes, 5 the only skill required in producing a design is the ability to follow a pattern.

It will also be apparent that a construction has been provided in which the lines of holes may be formed rapidly and inexpensively, and that such lines of holes will not 10 materially weaken the board.

I claim as my invention:

1. A tiled structure consisting of the combination of a supporting structure, a 15 sheet secured to said structure, said sheet having therein a plurality of rows of equidistant holes, and a plurality of tiles covering said sheet and cemented thereto, said tiles having members extending into said 20 holes to locate the tile.

2. A tiled wall comprising a plurality of studs, a foundation sheet secured to said studs, said sheet having in its face a plurality of parallel rows of holes, and a plurality 25 of metal plates covering said sheet and cemented thereto, each of said metal plates

having a plurality of rearwardly extending projections thereon adapted to engage the holes in said sheet.

3. A tiled wall comprising a framework, 30 a sheet secured to said framework, said sheet having in its face a plurality of holes arranged in rows to designate a number of geometrical figures on the face of said sheet, a plurality of tiles covering and cemented 35 to said sheet, and a plurality of means on said tiles extending into said holes properly to position said tiles on said sheet.

4. A tiled wall comprising the combination of a supporting structure, a sheet secured to said structure, said sheet having a plurality of rows of holes therein extending through said sheet to permit either face of said sheet to be exposed, and a plurality of tiles covering said sheet and cemented 45 thereto, said tiles having members thereon extending into said holes to locate said tile on the face of the sheet.

In testimony whereof, I have hereunto affixed my signature.

GEORGE D. HAINES.
